UNITED STATES PATENT OFFICE.

FRANKLIN L. GAINES, OF GRAND RAPIDS, MICHIGAN.

ROAD-FLOAT.

No. 918,993.

Specification of Letters Patent. Patented April 20, 1909.

Application filed August 10, 1908. Serial No. 447,773.

To all whom it may concern:

Be it known that I, FRANKLIN L. GAINES, a citizen of the United States of America, residing at Grand Rapids, in the county of Kent and State of Michigan, have invented certain new and useful Improvements in Road-Floats; and I do hereby declare the following to be a full, clear, and exact description of the invention, such as will enable others skilled in the art to which it appertains to make and use the same.

My invention relates to improvements in road floats, and its object is to provide a simple effective device having various new and useful features hereinafter more fully described and particularly pointed out in the claims.

My device consists essentially of a series of beams horizontally disposed, arranged in parallel relation and spaced apart, connecting bars pivotally attached thereto, whereby the beams are adjusted, and a brace adjustably connected thereto whereby the bars are held in adjustment at various distances from each other and overlapping each other more or less, a blade attached to the first beam of the series, the same being recessed at intervals at its lower edge and the metal between the recesses twisted to form diagonal cutting blades, and straight edged scraping blades attached to the remaining beams, as will more fully appear by reference to the accompanying drawings in which:

Figure 1 is a perspective of a device embodying my invention and adjusted for use; Fig. 2 a plan view of the same; Fig. 3 an enlarged detail of a portion of the cutting blade and beam in elevation; Fig. 4 the same showing an inverted plan; and, Fig. 5, a transverse section of the same on the line 5—5 of Fig. 3.

Like numbers refer to like parts in all of the figures.

1, 2, and 3 represent a series of beams horizontally disposed and spaced apart in parallel relation, said beams being preferably angle iron bars each with its horizontal member above and a downwardly extended vertical member at the rear. These beams are connected by channel bars pivotally attached thereto by bolts 11, whereby they are spaced apart at various distances as preferred, and will overlap and extend partially beyond each other in series according to adjustment. To adjust and hold these beams and bars, a brace bar 5 preferably of angle

iron is pivotally connected to the front beam 1 near one end thereof, and adjustably connected to the rear beam 3 near the other end by a bolt 6 adjustable in a series of 60 openings 7 in the horizontal member of the beam 3.

To the vertical member of the forward beam 1 is bolted a strip of metal near its upper edge arranged substantially vertical 65 and extending below the beam, that portion below the beam being recessed or slotted vertically at regular intervals and twisted to form diagonally disposed cutting blades which cut and turn the soil. To the vertical member of each remaining beam is attached a scraping blade 8 consisting of a rectangular strip of steel which smooths and levels the soil disintegrated by the cutting blades on the beam 1.

12 are shackles on the beam 1 by means of which any suitable means of moving the device forward may be attached. The tendency of the beams is to turn somewhat diagonal to the direction of movement due to 80 the laterally projecting position of the successive beams whereby the tendency of the device is to move the material longitudinally of the cutters and scrapers and thus more effectually pulverize and move the same, the 85 degree of projection and distance apart of the beams being determined by the adjustment of the brace bar 5 relative to the openings 7.

What I claim is:

1. A road float comprising a series of horizontally disposed beams spaced apart, bars connecting the beams and pivotally attached thereto, a brace bar adjustably connecting the beams, a disintegrating member attached 95 to the forward beam, and a straight edged scraper attached to each remaining beam.

2. A road float comprising three angle iron beams, two channel bars pivotally connected thereto and adjustably spacing the 100 same apart, a brace bar pivoted to one beam and adjustably connected to another beam, a plate attached to the forward beam and having its lower edge vertically recessed and twisted out of alignment forming inclined 105 cutters, and straight edged scraping blades attached to the remaining beams.

3. In a road float, the combination of three angle iron beams spaced apart in parallel relation and each having a horizontally disposed upper member and a vertically disposed rear member, two transverse channel

bars pivotally attached to the beams, a brace bar pivoted to the forward beam and adjustably attached to the rear beam, a disintegrating member attached to the forward beam and consisting of a plate projecting below said beam and having its lower part vertically recessed at intervals and twisted to form diagonally disposed blades, and a scraper blade consisting of a straight edged

rectangular plate attached to the vertical member of each of the other beams.

In testimony whereof I affix my signature in presence of two witnesses.

FRANKLIN L. GAINES.
